Primary Examiner — Elizabeth J Oswecki(74) *Attorney, Agent, or Firm* — Crossley & Stevenson
Intellectual Property Law(57) **CLAIM**

The ornamental design for a money order printing ATM, as shown and described.

DESCRIPTION

FIG. 1 is a front elevation view of a money order printing ATM showing our new design;

FIG. 2 is a rear elevation view thereof;

FIG. 3 is a right side elevation view thereof, the left side elevation view being a mirror image;

FIG. 4 is a top plan view thereof;

FIG. 5 is a bottom plan view thereof; and,

FIG. 6 is an isometric view thereof.

The cord is shown broken away in FIGS. 3–6 to indicate that no particular length is claimed.

1 Claim, 5 Drawing Sheets(56)
